SHEET MATERIAL DISPENSER

Patrick P. Howrilka, Union, N. Y.

Application April 1, 1955, Serial No. 35,319

Term of patent 14 years

(Cl. D4—3)

The figure is a perspective view of a sheet material dispenser showing my new design, the end of the dispenser not shown in said figure being identical to that shown.

The dotted line showing of a roll of sheet material is for illustrative purposes.

I claim:

The ornamental design for a sheet material dispenser, as shown and described.
